PULVERIZED COAL FEEDING APPARATUS
FOR FURNACES

William B. Rogers, Baltimore, Md.

Application August 2, 1939, Serial No. 288,016

9 Claims. (Cl. 302—17)

This invention is a novel pulverized fuel feeding apparatus for delivering powdered coal or the like suspended in air or gas into a burner, said apparatus being particularly adapted for domestic use and to be economically operated for delivering powdered coal in any amounts per hour within the complete range of domestic heaters.

Other minor objects of the invention will be hereinafter set forth.

I will explain the invention with reference to the accompanying drawings which illustrate one practical embodiment thereof to enable others familiar with the art to adopt and use the same; and will summarize in the claims, the novel features of construction, and novel combinations of parts, for which protection is desired.

In said drawings:

Fig. 1 is a transverse section through the apparatus on the line 1—1, Fig. 2.

Fig. 2 is a horizontal section through the apparatus on the line 2—2, Fig. 1.

Fig. 3 is a longitudinal section on the line 3—3, Fig. 2; and

Fig. 4 is an end view showing the driving means of the apparatus.

As shown, the apparatus is mounted in a skeleton frame having a rectangular base 1, and uprights 3 at the corners thereof connected by top bars 4 to form a rigid structure. A hopper 5 is suspended within the frame coextensive with the area of the top thereof, said hopper being contracted at its lower end towards one side of the frame, said hopper being provided with end plates 6, and side plates 7 converging at angles of approximately 27° from the vertical to meet the rounded lower end 6 of the hopper. The side plates 7 of the hopper are suspended at their upper ends on the top bars 4 of the frame, and are adapted to be jolted or shaken as herein-after described to insure proper and even feeding of the powdered fuel down into bottom 6 of the hopper.

From one end of bottom 6 of the hopper extends a tubular casting 2; and journaled in a bearing block 2a in the outer end of casting 2 and in a bearing 5a (Fig. 2) in the opposite end plate 5 of the hopper is a shaft 8 carrying a conveyor screw 9 adapted to move the powdered fuel from the bottom of the hopper through the casting 2, bearing block 2a in casting 2 being located beyond the outer end of screw 9.

The main function of the apparatus is to feed the proper amount of powdered coal as evenly as possible into the proper volume of air, and to

mix the two as thoroughly as possible before delivery thereof through the outlet duct of the apparatus into the burner attachment of the furnace. I have found that the major problem encountered in firing pulverized or finely divided coal, or other solid fuel, in small combustion chambers is to maintain an essentially smooth or even flow of coal and air into the combustion chamber so that the coal will be mixed perfectly with the primary air delivered by the fan or blower. In order to insure that the coal fed by screw 9 will be at an even rate, regardless of whether the hopper 5—7 is full of powdered coal or is nearly empty, I have devised a novel hopper agitator which will not only vibrate the coal directly over the screw 9 to create a uniform fluffiness in the mass of coal at this point, but will also vibrate the side walls 7 of the hopper, causing any coal therein to slide down properly, thereby eliminating tunnelling of the coal around and adjacent the screw 9. Of the two above mentioned functions of the agitators the most important, by far, is the conditioning of the coal directly above the screw 9. A number of simple mechanical devices have heretofore been designed for shaking down the coal in the hopper, but my novel agitator is the only one found which I have found will in fact cause the screw 9 to feed a constant amount of powdered fuel from the hopper whether the hopper is full or nearly empty.

As shown in Figs. 1 and 3, the opposite side plates 7 of the hopper are connected together by metal straps 11, bolted or riveted to the plates; and secured to the centers of straps 11 is a longitudinally disposed horizontal bar 12; and connected with the horizontal bar 12 adjacent the straps 11 are vertically disposed shaker bars 13 which extend downwardly with their lower ends terminating above and adjacent the screw shaft 8. Portions of the screw 9 are omitted in way of the lower ends of shaker bars 13, lugs 14x being provided on shaft 8, whereby as the shaft rotates the lugs 14x will strike the lower ends of shaker bars 13 and vibrate or jolt the hopper side plates 7, thereby positively shaking down the powdered fuel in the hopper into bottom 6 around screw 9. The above mentioned agitator 11—12—13—14 is essential in order to maintain the necessary even flow of coal required for efficient operation of the apparatus, and same cannot be eliminated without impairing the operation to such extent that it may be rendered impractical.

At the outer end of casting 2, is a head cast-

ing which includes a duct 14 having a horizontal air inlet 14a, said duct curving downwardly over and around one side of casting 2 as shown in Fig. 1, with its outlet 14b disposed vertically 5 and merging into a throat 15, the lower wall 15a of which is tangent to the casting 2 adjacent its bottom and slopes downwardly and laterally and terminates tangentially of a circular head 16 having a peripheral flange 16a (Fig. 2) said head 10 forming one end of a carburetor casing 37 disposed on a horizontal axis offset from and parallel with the shaft 8. An opening 16b in flange 16a is provided in way of the throat 15 forming an inlet into head 16, and the walls of duct 14 15 at the outlet 14b merge into the walls of the throat 15 and the flange 16a, whereby the throat 15 is connected in an airtight manner to the head 16.

In the bottom of casting 2 adjacent the outer 20 end of screw 9 is an opening 2b (Figs. 1 and 3) leading directly into throat 15, and as shown in Figs. 2 and 3 the inner end 2x of bearing block 2a of casting 2 is cut in a plane disposed at such angle to the axis of shaft 8 that the coal, fed 25 by screw 9, will be directed downwardly and laterally by the face 2x directly through opening 2b and into throat 15. A flap valve 17 is suspended from a rock shaft 18 journaled within the side walls of throat 15 immediately below the end of 30 the inner wall of outlet 14b of duct 14, said flap valve being of length sufficient to normally contact the bottom plate 15a of throat 15 when the valve is in vertical position shown in Fig. 1, in which said valve substantially closes communication from opening 2b into the head 16. An arm 17a on shaft 18, exterior to the throat, is connected by a spring 17b to a fixed lug 15x on the exterior of the throat, said spring tending to normally maintain the flap valve 17 closed.

40 A centrifugal blower 19, discharges air into the inlet 14a of duct 14, the blower taking in air around the shaft 19a of its impeller 19b and delivering same under pressure into the duct 14. A rubber, rubberized, or other elastic collar 20, secured by band 20a, connects the outlet of fan 19 with the inlet 14a of duct 14.

45 Shaft 19a of blower 19 extends through an adjustable bearing 21, and is preferably rotated by a belt 22 running over pulley 23 on fan shaft 19a and over a pulley 24 on the shaft 25a of the prime mover 25, preferably an electric motor, disposed coaxially of the head 16. Bearing 21 preferably comprises a tubular body open at each end, and provided with ball bearings 21a for shaft 19a. Body 21 is provided with a pedestal 21b having anchor bolts 21c the heads of which engage elongated slots 1x in base 1, whereby when bolts 21c are loosened the bearing 21 and the blower 19 which is supported thereon by clips 19x (Fig. 2) 50 may be shifted as a unit towards or from the motor 25 to adjust the tension of belt 22.

55 Mounted on fan shaft 19a is a second belt pulley 26 opposite a pulley 27a on the driving shaft of a speed change mechanism 27 conventionally shown in Fig. 2, a drive belt 28 running around pulleys 26 and 27a. The driven shaft 27b of the speed change mechanism is axially aligned with screw shaft 8, and a coupling 8x connects shafts 8 and 27b, whereby the conveyor screw may be 60 driven at various speeds from the blower shaft 19a.

75 The carburetor comprises a cylindrical casing 37 open at one end but having its perimeter at the open end offset as at 37a (Fig. 2) to fit with in the peripheral flange 16a of head 16, the parts

being secured together by any desired means, and said head 16 closing the open end of casing 37. The opposite end of casing 37 is closed by plate 37b provided with an axially disposed outlet 37c adapted to be directly connected with the fuel burner (not shown). Within casing 37, axially thereof, is a shaft 28 connected directly with shaft 25a of motor 25, said shaft extending through a stuffing box 28a in head 16.

On shaft 28, within the carburetor, are a plurality of stirrer blades 29 (four being shown) adapted to stir up the powdered fuel and to break up and thoroughly reduce any lumps or cakes of fuel, whereby the air within the carburetor may readily pick up the powdered fuel and pass the mixture of fuel and air directly into the outlet 37a and into the burner. The blades 29 are designed and arranged to give the greatest possible amount of turbulence, and are not in any way to be confused with fan blades, as the alternate blades 29 will actually act to retard the flow of air rather than assist same, and thus the coal and air is subjected to a thorough mixing due to the fact that the fuel and air have to work against the alternate whirling blades in passing through the carburetor to the outlet 37c.

As shown in Figs. 1 and 2 each blade 29 comprises a flat plate having a narrow central portion provided with a hole to receive shaft 28 upon which same is mounted. Blades 29 are symmetrical and flare outwardly in width and have their outer portions crimped as at 29c, holes 29d being provided in the inner portions of the blades. Each of blades 29 is mounted on shaft 28 at such angle that the air current therefrom will be directed in the opposite direction from the adjacent blade, whereby the fuel and air mixture in the carburetor will be subjected to a thorough mixing in working towards outlet 37c.

Operation

40

In operation, the prime mover 25 rotates blower shaft 19a, which shaft also rotates screw shaft 8 through the speed reducing mechanism 27 to feed powdered coal from the hopper through casting 2 and into throat 15. The speed reducing mechanism 27 may be set to regulate the amount of coal delivered to the air current in duct 14, while rotating shaft 8 will simultaneously actuate the agitator 11-12-13 so that the pulverized or finely divided coal, or other solid fuel in the hopper is fed in a steady smooth or even stream into the throat regardless of whether the hopper is full or is nearly empty, since the coal will be vibrated by the agitator not only directly over and around the screw 9, creating a uniform fluffiness in the coal at this point, but the sides 1 of the hopper will also be vibrated to cause any coal in the hopper to slide down properly, eliminating tunnelling of the coal around screw 9.

55 The screw 9 feeds the coal into throat 15 against the light but steady pressure of the spring loaded flap valve 17 which tends to discharge the coal into the air currents in the throat in a smooth steady stream. Beyond flap valve 17 the coal is picked up by the air currents and carried into the carburetor 37 where the powdered coal will be thoroughly mixed with and carried over by the air through the outlet 37c directly to the burner (not shown), the rapidly 60 rotating blades 29 insuring that all lumps or adhering particles of coal will be reduced as said blades are arranged to give the greatest possible amount of turbulence. The coal and air fuel mixture is taken off the back 37b of the car- 75

buretor 37 at the axis of the mixing blades 29.

I claim:

1. In apparatus of the character specified, a housing for powdered material having an outlet; means including a screw shaft in the housing to convey the material to said outlet; a carburetor casing having an inlet and outlet; an air duct extending adjacent the housing outlet and into the carburetor inlet; an offset throat in said duct communicating with the housing outlet; means for forcing air under pressure into said duct; a yieldable flap in said throat at the housing outlet; the housing outlet being disposed above and to one side of the carburetor inlet; and said air duct having a bottom wall sloping downwardly from the housing outlet to the carburetor inlet and substantially tangent to the carburetor casing.
2. In apparatus of the character specified, a housing for powdered material having an outlet; means including a screw shaft in the housing to convey the material to said outlet; a carburetor casing having an inlet and outlet; an air duct extending adjacent the housing outlet and into the carburetor inlet; an offset throat in said duct communicating with the housing outlet; means for forcing air under pressure into said duct; a yieldable flap in said throat at the housing outlet; the housing outlet being disposed above and to one side of the carburetor inlet; said air duct having its bottom wall sloping downwardly from the housing outlet to the carburetor inlet and substantially tangent to the carburetor casing; said carburetor being cylindrical; an axially disposed shaft in said carburetor; a series of radial blades on said shaft; and means for rotating the shaft to move the blades in a direction opposite to that of the air and coal entering the inlet.
3. In apparatus of the character specified; a housing having an outlet; means including a screw shaft for conveying material through the housing to said outlet; a carburetor having a tangential inlet and an axial outlet; the housing outlet being disposed above and to one side of the carburetor inlet; an air duct extending adjacent the housing outlet and into the carburetor inlet, the bottom wall of said duct sloping downwardly from the housing outlet to the carburetor inlet; an offset throat in said duct communicating with the housing outlet; a yieldable flap valve in said throat at the housing outlet; and means for forcing air into the air duct.
4. An apparatus as set forth in claim 3, said carburetor being cylindrical; an axially disposed shaft in said carburetor; a series of radial blades on said shaft; and means for rotating the shaft

to move the blades in a direction opposite to that of the air and coal entering the inlet.

5. In apparatus as set forth in claim 3, said carburetor being cylindrical and its inlet being disposed at one end, and its outlet being disposed at the other end; an axially disposed shaft in said carburetor; and a series of flat blades on said shaft arranged at angles to the axis of the shaft, adjacent blades of the series being inclined so as to produce air currents in opposite directions, whereby a maximum turbulence will be produced within the carburetor between the inlet and outlet.

6. In apparatus of the character specified; a housing having an outlet; means including a screw shaft for conveying material through said housing to said outlet; a carburetor adjacent the housing having a tangential inlet and an axial outlet; an air duct extending adjacent the housing outlet and into the carburetor inlet; an offset throat in said duct communicating with the housing outlet; means for forcing air under pressure into said air duct; a yieldable flap valve in said throat at the housing outlet; said carburetor being cylindrical; an axially disposed shaft in said carburetor; and a series of flat blades on said shaft arranged at angles to the axis of the shaft, adjacent blades of the series being directed to produce air currents in opposite directions, whereby a maximum turbulence will be produced within the carburetor between the inlet and outlet; and the inlet and outlet being disposed at opposite ends respectively of the series of blades.

7. In apparatus as set forth in claim 6, said blades being of narrow width at their hub portions and widening towards their outer ends, the outer portions of the blades being crimped.

8. An apparatus as set forth in claim 6, the housing outlet being disposed above and to one side of the carburetor inlet; and said air duct having a bottom wall sloping downwardly from the housing outlet to the carburetor inlet and substantially tangent to the carburetor casing.

9. An apparatus as set forth in claim 6, the housing outlet being disposed above and to one side of the carburetor inlet; said air duct having a bottom wall sloping downwardly from the housing outlet to the carburetor inlet and substantially tangent to the carburetor casing; said carburetor being cylindrical; an axially disposed shaft in said carburetor; a series of radial blades on said shaft; and means for rotating the shaft to move the blades in a direction opposite to that of the air and coal entering the inlet.

55

WILLIAM B. ROGERS.
